(57) **CLAIM**

The ornamental design for a light fixture, as shown and
described.

DESCRIPTION

FIG. 1 is a bottom perspective view of the light fixture.
FIG. 2 is a right side elevation view of the light fixture of FIG.
1, it being understood that all side elevation views are identical
to the right side elevation view.

FIG. 3 is a top plan view of the light fixture of FIG. 1; and,
FIG. 4 is a bottom plan view of the light fixture of FIG. 1.
Portions or features of the light fixture not shown in the
drawings form no part of the claimed design. The broken lines
in the drawings illustrating portions of the light fixture form
no part of the claimed design.

1 Claim, 4 Drawing Sheets
